GRID FOR ELECTRON DISCHARGE DEVICES

Gerald Glen Carne, Rockaway, N. J., assignor to
 Radio Corporation of America, a corporation
 of Delaware

Application December 17, 1948, Serial No. 65,817

5 Claims. (Cl. 250—27.5)

1

The present invention relates to improvements in electron discharge devices of the gas discharge type, and more particularly to an improved amount for such devices including an improved grid.

Some types of electron discharge devices, such as thyratrons, employ a control grid made of sheet metal, the wider surfaces of which are disposed parallel to the path of electron flow. A sheet metal type of control grid is suitable for thyratrons since in most instances the nature of the control function is to block electron flow through the device, except when the grid is excited by a critical voltage in response to which it permits such flow. The control grid is in most instances inoperable to stop the flow and such stoppage is usually accomplished by circuits external of the device. A sheet metal type of grid is well suited for this type of control.

One of the problems presented by this type of grid involves the requirement that the grid originally during manufacture of a device be critically spaced from other electrodes of the device for performing its critical control of the initiation of electron flow therein, and that this spacing and the form of the grid be maintained without change during useful life of the device.

Another problem concerns the manner of support of the grid in an electron discharge device. Where the grid is made of sheet metal it is desirable that all legs or elements thereof be directly supported on relatively rigid support structures. Sheet metal grids heretofore employed in thyratrons have included elements that depend for their support on other elements of the grid. This type of support weakens the grid structure, particularly since the elements thereof serving the dual function of the active portion of the grid as well as support means, may be weakened during use so as to distort an active portion of the grid out of its originally and critically adjusted position, thereby rendering the device unsuited for fine control purposes.

The manner of support of a grid can also give rise to another problem. For example, one type of grid heretofore used and designed for support between two spacer plates, is provided with bearing surfaces engaging inner faces of said plates. Where the spacer plates are fixed against relative movement with respect to each other, expansion of the grid in response to heat resulting from certain operation conditions may cause the grid to collapse or become distorted and this may contribute to faulty operation of the device in which it is used.

A further problem is encountered in respect

2

to the cost of the grid. Grids of the type referred to have heretofore comprised two parts welded together at two displaced locations. In addition, they have required two forming operations, one for forming each part prior to welding the parts together, and the other for forming the grid after the parts have been welded together. This requires equipment and operator time that appreciably adds to the cost of the device in which the grid is used.

It is therefore the object of the invention to provide an improved mount for an electron discharge device.

Another object is to provide an improved support for a grid in the mount of an electron discharge device.

A further object is to provide an improved grid structure contributing to good support thereof in an electron discharge device and to good operation of said device.

An additional object of the invention is to provide an improved sheet metal grid of relatively simple structure lending itself to good support in an electron discharge device and resulting in economies in the manufacture of the device.

Another object is to provide a one-piece sheet metal grid requiring only one forming operation.

A further object is to provide a one-piece sheet metal grid adapted to be supported in such a manner that its form is preserved against distortion during operation of a device in which it is employed.

Another object is to provide a one-piece sheet metal grid that contributes to an effective support thereof against displacement with respect to other electrodes in a device and against deformation or collapse in response to thermal operating conditions of the device in which it is used.

A further object is to provide an improved mount including a one-piece grid and supports therefor wherein the supports and the grid structure cooperate to support the grid elements against displacement with respect to each other and with respect to other electrodes of a device in which it is used.

Another object is to provide a sheet metal grid and support therefor that contributes to ease in mounting the grid in an electron discharge device.

Further objects and advantages will become evident as the description continues.

Referring now to the drawing:

Figure 1 shows a longitudinal section along lines 1—1 of Fig. 2, of a thyratron type of electron discharge device in which my novel grid may be used;

Figure 2 represents a cross-section along the lines 2-2 of Figure 1 and indicates the cross-sectional structure of the device shown in Figure 1 as well as a portion of my novel grid;

Figure 3 is a cross-section of the mount along the lines 3-3 of Figure 2 and shows one side edge and the general U-shape form of my novel grid and the manner in which it is supported by the insulating spacer plates of the device;

Figure 4 is a top view of Figure 3 and shows the upper end of the mount and the manner in which my novel grid is supported at the upper end thereof;

Figure 5 is a perspective view of my novel grid after it has been subjected to the one forming operation required in accordance with the invention; and

Figure 6 is a perspective view of a prior art sheet metal grid including two parts welded together at two locations and requiring two forming operations, and provided with bearing surfaces engaging the inner faces of two spacer members.

Considering the drawing in more detail, there is shown in Figure 1 a thyratron type of electron discharge device in which my novel grid may be used. The device includes an envelope 10 closed at one end by a header or base 11 having contact prongs 12. The envelope contains a suitable gas permitting a discharge therethrough and an electrode mount including a screen grid 13, having beam forming members 14, shown best in Figure 2, a cathode 15, a plate 16 and a sheet metal control grid 17 supported between a pair of substantially parallel axially displaced insulating spacer members or plates 18 and 19. The grid 17 is supported in the device in such a manner that its flat surfaces lie in planes parallel to the direction of electron flow in the device during discharge therethrough.

According to the invention, my novel sheet metal grid 17 comprises a one-piece structure, shown best in Figure 4, having legs 20 and 21 and transverse portion 22. Leg 20 may be longer than leg 21 for a purpose to be described.

Further, according to my invention the insulating spacer members 18 and 19 are provided with slots 23, 24, 25 and 26 for receiving the legs 20, 21. When assembled in an electron discharge device, as shown in Figures 3 and 4, the legs 20 and 21 of my novel grid extend through the slots 23 and 24 in the upper spacer member 18, with the transverse portion 22 bearing against the upper face of this spacer member. The lower portions of the legs extend through slots 25 and 26 in the lower spacer member 19. Leg 20 may be longer than leg 21 to permit it to extend farther beyond the lower face of the lower spacer member for convenience in connection to a lead-in.

The slots 23, 24, 25 and 26 in the upper and lower spacer members 18 and 19 are dimensioned to receive the grid legs 20 and 21 in a snug fit. The slots in each of the spacer members are critically spaced from each other so as to receive the legs 20 and 21 of my novel grid without distorting its U-shaped form or disturbing the critical predetermined spacing between the legs required for a sharp response to a predetermined voltage excitation of the device in which it is used. The slots referred to, in the spacer members 18 and 19 therefore properly located my grid in the mount of a device in which it is used and serve to restrain the grid from displacement out of its properly located position.

This restraint against displacement of my grid is mainly accomplished as the result of the snug support provided at each end of the legs 20 and 21 thereof by the snug engagement therewith of the edges of slots 23, 24, 25 and 26. Thus, any transverse displacement of the grid with respect to the mount is prevented by the snug fit of the legs in the slots referred to. While this snug fit also contributes to a restraint of longitudinal movement of the grid with respect to the mount, such movement is in the main prevented by the abutting engagement between the transverse portion 22 of my grid and the top surface of the upper spacer member 18, and by the connection of a lead-in 27 to leg 20 in a weld 28 adjacent the bottom surface of the lower spacer member 19.

The engagement between the transverse portion 22 and the spacer member 18 and the engagement between the weld connection 28 and the spacer member 19, effectively prevent longitudinal movement of the grid as a whole with respect to the mount. However, these engagements do not prevent longitudinal movement of portions of the grid legs that might be caused by expansion thereof in response to heat during certain operating conditions. This is for the reason that such expansion involves movement of longitudinal portions of the grid legs in opposite directions simultaneously and in directions opposite to that in which the engagements referred to provide restraints.

The freedom of my grid to move longitudinally in the manner indicated in response to expansion thereof is an advantageous feature of my invention. It permits absorption of the expansion of my grid in linear elongation thereof and prevents a buckling or collapse that might occur in the absence of such freedom to move longitudinally. Since as has been indicated herein the sharpness of control afforded by a sheet metal grid is substantially entirely dependent on its spacing with respect to the electrodes in a device, a buckling or deformation of portions of the grid would change their relative positions in the mount and result in a loss in sharpness of control of the grid. It will further be noted that longitudinal displacement only of my grid has no adverse effect on the sharpness of its control function. This is for the reason that my grid is longitudinally uniform in structure between the spacer members 18 and 19, which define the portion of the device in which the grid is operative.

It will be appreciated from the foregoing that my novel grid has many advantages over prior art types of sheet metal grids, one of which is shown in Figure 6. The grid shown in Figure 6 is a common form of grid heretofore used in electron discharge devices such as thyratrons. It includes two parts 29, 30 which are joined in welds 31, 32, each part terminating at a location intermediate the other part to provide bearing ends 33, 34 for bearing against the inner surfaces of spacer members, not shown. This grid is objectionable in that it requires two forming steps, one for forming each of the members 29, 30 prior to joining them, and the other for forming the grid structure after the members thereof have been welded together. And additional objection to this grid resides in the fact that the bearing end surfaces 33, 34 prevent longitudinal displacement of portions of the grid in response to expansion thereof, with the result that such an expansion is permitted to find an outlet in a

buckling or other form of distortion or collapse of the grid.

In making my novel grid there is first stamped from sheet metal stock a rectangular form having a predetermined width and length required for a particular grid. This rectangular form is then bent by a tool, not shown, to provide a U-shaped form shown in Figure 5. This forming operation is accurately performed and no further forming action is necessary. The mounting operation involves threading the legs of my grid through the slots previously referred to in the spacing members 18 and 19. If during the manual handling of the grid after its formation and prior to its insertion in the slots referred to, the legs thereof should be disposed out of true parallel relation, such deforming of the grid legs is corrected by the novel feature of my invention residing in the critical spacing of the slots in each of the spacer plates referred to, and the snug fit of the legs in said slots. According to my invention, therefore, any inaccuracy in the spacing between the legs of my grid resulting from handling is effectively corrected and the correct spacing preserved during the life of the device in which my grid is used.

After the grid is threaded into the slots referred to the longer leg may be connected to a lead-in as described above.

The fabrication of my novel grid and its assembly in a mount are, therefore, characterized by simplicity and economy. In addition to being easily and economically made and mounted, my grid is also superior to prior art grids in operation and contributes substantially to the good functioning of a device in which it is employed.

Various modifications may be made in my novel grid and in the manner of its support in an electron discharge device without departing from the spirit of the invention which I desire to be given a scope commensurate with the appended claims.

What I claim is:

1. A mount for an electron discharge device including spaced insulating spacer members and a grid disposed between said members, said grid comprising a U-shaped structure made of sheet metal having parallel legs lying in parallel spaced planes and a transverse portion, said spacer members each having two parallel and coextensive slots spaced from each other by a distance equal to the length of said transverse portion for snugly receiving said legs with said transverse portion abutting against one face of one of said spacer members, and the free ends of said legs extending beyond the remote face of the other of said spacer members, whereby said grid is free to expand longitudinally without disturbing electrode spacings in said device.

2. A mount for an electron discharge device including axially displaced insulating spacer members and a grid disposed between said members, said grid comprising a U-shaped structure made of sheet metal having parallel legs lying in parallel planes and a transverse portion, said spacer members each having two coextensive slots spaced from each other by a distance equal to the length of said transverse portion for snugly receiving said legs with said transverse portion abutting against one face of one of said spacer members, the free ends of said legs extending beyond the remote face of the other of said spacer members, and a lead-in connected to one of said legs adjacent said remote face of said other of said spacer members, whereby said grid is re-

strained against transverse bodily movement with respect to said spacer members, but is permitted to expand longitudinally in response to thermal expansion without disturbing its space relationship with respect to other electrodes in said device.

3. A mount for an electron discharge device including two parallel axially displaced spacer members and electrodes mounted between said members, said electrodes including a cathode, an anode and a grid disposed between said cathode and anode, said grid being made of sheet metal and including two straight legs lying in two parallel planes and extending from one of said spacer members to the other, the planes of said legs also being parallel to a plane including said cathode and said anode, whereby the edges of said legs are normal to the path of electron flow from said cathode to said anode, said spacer members having coextensive slots for receiving end portions of said legs in snug fits, said grid having a transverse portion connecting adjacent ends of the legs at one end of said grid and abuttingly engaging the outer face of one of said members, whereby said grid is securely supported by said spacer members against lateral movement but is free to move longitudinally in response to thermal expansion thereof without disturbing electrode spacings in said device.
4. A mount for an electron discharge device including two spaced flat spacer members and electrodes disposed between the inner faces of said members, said electrodes including a one-piece sheet metal grid having two legs, said spacer members having coextensive slots disposed in critical space relationships with respect to each other, and with respect to others of said electrodes for receiving end portions of said legs in snug fits, whereby said grid is properly positioned in said mount on engagement of said end portions of the legs thereof by said slots and free to move longitudinally without disturbing spaced relations of elements of said device.
5. A mount for an electron discharge device including two axially displaced parallel spacer plates and electrodes disposed between the inner faces of said plates, said electrodes including a sheet metal grid having two flat and straight parallel legs and a flat transverse portion connecting two adjacent ends of said legs, said plates having slots receiving the ends of said legs, a flat surface of said transverse portion engaging the outer face of one of said plates, the free ends of said legs extending through the slots in the other of said plates and beyond the outer face thereof, and a lead-in welded to one of said legs, said lead-in engaging said outer face of said other of said plates whereby said grid is supported against bodily longitudinal movement while capable of sectional longitudinal movement in response to thermal expansion thereof without disturbing the space relation of said grid with respect to others of said electrodes disposed between said plates.
